(57) **CLAIM**

I claim, the ornamental design for a bottle, as shown and described.

DESCRIPTION

© 2011 Teresa Andreotti. Portions of the disclosure of this patent document contain material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is an assembled, perspective view of the bottle showing my new design thereof;

FIG. 2 is an assembled, front view thereof;

FIG. 3 is an assembled, side view thereof taken from the right of FIG. 1;

FIG. 4 is an assembled, rear view thereof;

FIG. 5 is an assembled, side view thereof taken from the left of FIG. 1;

FIG. 6 is an assembled, top view thereof;

FIG. 7 is an assembled, bottom view thereof; and,

FIG. 8 is an exploded, perspective view thereof.

The broken line showing is for illustrative purposes only, and forms no part of the claimed design.
